UNITED STATES PATENT OFFICE.

ERNEST E. EINFIELDT, OF DAVENPORT, IOWA, ASSIGNOR TO G. WATSON FRENCH, NATHANIEL FRENCH, JOSEPH L. HECHT, AND W. H. STACKHOUSE, OF DAVENPORT, IOWA, COMPOSING FIRM OF FRENCH & HECHT.

METHOD OF MAKING WHEEL HUBS.

1,409,213.

Specification of Letters Patent. Patented Mar. 14, 1922.

Original application filed April 15, 1919, Serial No. 290,276. Divided and this application filed November 3, 1919. Serial No. 335,494.

To all whom it may concern:

Be it known that I, ERNEST E. EINFIELDT, a citizen of the United States, residing at Davenport, in the county of Scott and State 5 of Iowa, have invented certain new and useful Improvements in Methods of Making Wheel Hubs, of which the following is a specification, reference being had therein to the accompanying drawing, being a division 10 of original application filed April 15, 1919, Serial No. 290,276.

This invention relates to the manufacture of tubular metal wheel hubs, more particularly of the form in which a circumferential 15 groove or spoke chamber is provided to receive the heads on the inner ends of the spokes, by which the latter are riveted to the hub, the object of the invention being to provide a hub of great strength and durability which will withstand the severe 20 strains imposed upon it in the use of the wheel, especially at the points where the spokes are secured to the hub. With these ends in view my invention consists of an 25 improved method of forming the hub, in which method a plate or blank is coiled or bent on itself into cylindrical form and the convolutions are caused to interlock with each other by interfitting protuberances and 30 cavities on the respective convolutions, whereby there is formed a reinforced spoke chamber on the interior of the hub.

The interlocking of the convolutions may be brought about in various ways. For instance, the blank may be provided with a 35 groove in one side and a corresponding rib or protuberance on the other side and coiled on itself to cause the protuberance on the inner convolution to register with and seat 40 on the groove on the next outer convolution; or the grooves and protuberances may be formed and caused to interlock at the same time that the blank is coiled; or again the grooves and protuberances may be 45 formed and cause to interlock after a plain blank has been coiled into cylindrical form.

I prefer however to adopt the first plan mentioned, and in the accompanying drawings I have illustrated a form of blank suitable 50 for the purpose. It will be understood however that the invention is not limited to

this particular plan, but in its broader scope as claimed, the invention embraces as well the alternate plans above mentioned.

In the accompanying drawings:

Fig. 1 is a plan view of a blank for forming a hub in accordance with the preferred manner of carrying out my improved method.

Fig. 2 is a longitudinal section through the completed hub produced by my method, the spokes being shown as riveted thereto.

Fig. 3 is an end view of the same, with parts broken away.

Fig. 4 is an edge view of the blank of Fig. 1.

Referring to the drawings:

In the accompanying drawings I have illustrated my invention as applied to the formation of a hub having two circumferential spoke chambers to receive the heads on the inner ends of two rows or ranks of spokes, but it will be manifest that the invention is not limited to the formation of a hub of this form, but it is applicable as well to a hub formed with but a single circumferential chamber to receive a single row or rank of spokes.

In carrying my invention into effect, in connection with a hub of the form illustrated, I provide a flat metal plate or blank 1 having therein two straight parallel grooves 2 formed by bending the metal of the blank outwardly in two parallel lines or areas, and thereby producing on the opposite side of the blank, two ribs or protuberances 3 corresponding in location to the grooves. The blank thus formed is next, by suitable means or instrumentalities, bent or coiled upon itself into cylindrical form, thereby producing a number of convolutions or layers arranged one within the other, there being in the present instance two convolutions, an inner one 4 and an outer surrounding one 5 as shown in Figs. 2 and 3, 95 which convolutions have circumferentially extending inner grooves and corresponding circumferentially extending outer protuberances. In the coiling or bending operation, these grooves and protuberances are caused 100 to register with each other in the successive convolutions, the protuberance on the inner

convolution seating in the inner groove on the surrounding next outer convolution, thereby interlocking the two convolutions with each other. As a result of this mode 5 of procedure, a cylindrical hub structure is produced having on its interior circumferential grooves or spoke chambers, which in the completed wheel will receive the heads 7 on the inner end of the spokes 8, these spoke 10 chambers, due to the several layers or convolutions of the material, being reinforced and strengthened so that they will be well adapted to resist the severe strains placed upon them in the use of the wheel in practice. The several coils or convolutions may 15 be connected together by suitable means to prevent them from unwinding so as to preserve the cylindrical form of the structure. This may be effected, for instance, by spot-welding the contiguous surfaces of the convolutions; or dependence may be placed on the connection of the spokes thereto, which spokes, as shown, are extended at their inner ends through registering openings in 20 the two convolutions, and are riveted to the same by the inner heads 7 before alluded to, and outer shoulders 9, which latter bear against the outer side of the outer coil.

The hub structure formed as above set 30 forth, being made from sheet or plate metal, is economical to manufacture, and by reason of the several convolutions or layers of material surrounding each other, and the interfitting of the grooves and protuberances, a 35 structure of great strength and resisting properties is produced.

It will be obvious that in forming a hub to accommodate but a single row of spokes, the procedure would be the same as that set 40 forth above, except that instead of the blank being formed with two grooves and corresponding protuberances, it would have but a single groove and a corresponding protuberance.

45 Instead of forming the spoke chamber as a continuous circumferential groove, it may be made up of a number of cavities and corresponding protuberances to receive the ends of the individual spokes, and the convolutions caused to interlock with each other by 50 the fitting of the protuberances on an inner

convolution in the registering cavities on a surrounding convolution.

Having thus described my invention, what I claim and desire to secure by Letters Pat- 55 ent is as follows:

1. The method of making tubular metal wheel hubs, which method consists in providing a blank, forming a cavity in one side thereof and a corresponding protuberance on the other side, coiling said blank on itself to cause the protuberance on an inner convolution to seat in the cavity in the surrounding convolution to interlock said convolutions with each other and thereby form a reinforced spoke chamber on the interior of the hub, and fastening said convolutions together in their interlocked relations to preserve the tubular form of the same. 60

2. The method of making tubular metal wheel hubs with circumferential spoke chambers, which method consists in providing a blank, forming a groove in one side thereof and a corresponding protuberance on the other side, coiling said blank on itself to cause the protuberance on an inner convolution to seat in the groove in the surrounding convolution and thereby interlock the convolutions with each other to produce a circumferential spoke chamber on the interior 65 of the hub, and fastening said convolutions together to preserve the tubular form of the hub. 70

3. The method of making tubular metal wheel hubs with circumferential spoke 80 chambers, which method consists in providing a blank, forming a groove in one side thereof extending throughout the length of the blank and a corresponding protuberance on the other side, coiling said blank on itself 85 into cylindrical form to cause the protuberance on an inner convolution to seat in a groove on the next outer convolution, thereby interlocking the convolutions with each other and producing a circumferential spoke 90 chamber on the interior of the hub, and fastening said convolutions together to preserve the tubular form of the hub. 95

In testimony whereof, I have affixed my signature hereto.

ERNEST E. EINFELDT.
